WINDOW CONSTRUCTION

Louis H. Morin, New York, N. Y., assignor to
 Nicholas E. Griffin, South Pasadena, Calif.

Application October 17, 1940, Serial No. 361,476

5 Claims. (Cl. 20—53)

This invention relates to a window construction. More particularly, this invention relates to a window construction of the general character which is disclosed in the Nicholas E. Griffin Patent No. 2,199,562 dated May 7, 1940, on a Window construction. The window construction which forms the subject matter of the above-identified patent embodies a group of movable window panes or sections, which are movable about horizontally extending axes, into and out of open and closed positions, and a vertically extending and horizontally movable weather-stripping member which is adapted to engage one side or vertically extending marginal edge portion of each of the window panes or sections so as to effect a weather-stripping engagement between the vertically extending edge portions of the window panes or sections when the latter are in closed position but so as to enable the window panes or sections to be moved into and out of open and closed positions.

An object of the present invention is to provide, in a window construction of the general character which is disclosed in the above-identified Griffin Patent No. 2,199,562, a new and improved and simplified construction for moving the window panes or sections into and out of open and closed positions, and a new and improved and simplified construction for moving the weather-stripping member into and out of weather-stripping engagement with the window panes or sections.

Another object of the present invention is to provide a new and improved window construction of the character which is herein described and shown.

Other and further objects of the present invention will be apparent from the following description and claims and are illustrated in the accompanying drawings which, by way of illustration, show preferred embodiments and the principle thereof and what I now consider to be the best mode in which I have contemplated applying that principle. Other embodiments of the invention embodying the same or equivalent principles may be used and structural changes may be made as desired by those skilled in the art without departing from the present invention and the purview of the appended claims.

In the drawings,

Fig. 1 is a front elevational view of a window construction embodying the present invention;

Fig. 2 is a side elevational view of the window construction which is shown in Fig. 1;

Fig. 3 is an enlarged horizontal sectional view on line 3—3 in Fig. 1;

Fig. 4 is an enlarged horizontal sectional view on line 4—4 in Fig. 1;

Fig. 5 is a fragmentary front elevational view of the window construction which is shown in Figs. 1 to 4, inclusive; and

Fig. 6 is a fragmentary front elevational view of a modified form of construction of the present invention.

A preferred form of the present invention is shown in Figs. 1 to 5, inclusive, and comprises a window casement 10 which may be made in any suitable design and in any suitable material such, for example, as wood, metal and the like, inasmuch as the particular design of the window casement is not essential to the present invention.

The particular form of the window casement 10 which is illustrated in Figs. 1 to 5, inclusive, of the drawings includes a box-like housing 11 having a portion or side wall 12 which forms one side wall of the window casement 10, (Figs. 3 and 4). The window casement 10 also includes a side wall 13, a top wall 14, and a bottom wall 15, and the housing 11 (Figs. 3 and 4) also includes a side wall 16 and end walls 17 and 18.

The window construction which forms the present invention includes a plurality of normally vertically extending window panes or sections 19, 20 and 21 each of which is mounted in a frame 22, 23 and 24, respectively, these frames being made of any suitable material such as wood, metal or the like. Each of these window frames 22, 23 and 24 has a vertically extending side rail or portion (25, 26 and 27, respectively) and these side rails or portions 25, 26 and 27 are swingingly mounted on trunnions 28, 29 and 30, respectively, for movement about their horizontal axes (Fig. 1) into and out of open and closed positions. Each of these trunnions 28, 29 and 30 has its outer end portion fixedly mounted in the adjacent side wall 13 of the window casement 10 and each of these trunnions 28, 29 and 30 has the adjacent rail (25, 26 or 27) of the corresponding window frame (22, 23 or 24) slidably mounted thereon, for a reason which will be explained presently.

Formed in the inner surface of the vertically extending side wall 13 of the window casement 10 is a vertically extending groove 31 (Fig. 3) and a portion of each of the side walls or rails 25, 26 and 27 of the window frames 22, 23 and 24 is disposed in this groove 31 when said window frames are in closed position, as shown in Fig. 3.

Formed in the side wall 12 of the window casement 10 is a vertically extending slot 31a (Figs. 3 and 4) and slidably mounted for horizontal movement in this slot 31a is a vertically extending weather-stripping member 32. Formed in the inner surface of this weather-stripping member 32 is a vertically extending weather-stripping groove 33 (Figs. 3 and 4) and a portion of each of the vertically extending side walls or rails 34, 35 and 36 of the window frames 22, 23 and 24, respectively, is disposed in the vertically extending weather-stripping grooves 33 when the window panes are in closed position, as shown in Fig. 3.

Attached to the vertically extending side wall or rail 34 of the window frame 22, as at 37 (Fig. 1) is a horizontally extending shaft 38; similar shafts 39 and 40 being similarly attached to the vertically extending side walls or rails 35 and 36 of the window frames 23 and 24, as at 41 and 42, respectively, (Figs. 1 and 4). Each of these shafts, 38, 39 and 40 is slidably and horizontally projected through an opening, as 43 (Fig. 4) which is formed in the vertically extending weather-stripping member 32. Each of these shafts 38, 39 and 40 has a squared outer end portion (Fig. 2) and mounted on the squared outer end portions of these shafts are gears 44, 45 and 46, respectively. These gears 44, 45 and 46, respectively, are located in the box or housing 11 and mesh with worms 47, 48 and 49 which are mounted on a vertically extending operating rod or shaft 50 which is slidably mounted in the housing 11 for vertical movement therein. A compression spring 51 is arranged upon the lower end portion of the vertically extending operating rod 50 and tends normally to urge the vertically extending operating rod or shaft downwardly.

Fixed on each of the shafts 38, 39 and 40, outwardly of the weather-stripping member 32, is a collar 67, the purpose of which will be described hereinafter.

Splined on the vertically extending operating rod 50, adjacent the lower end thereof, (Figs. 1 and 2) is a beveled gear 52 and this beveled gear 52 meshes with a beveled gear 53 (Figs. 1 and 2) which is mounted upon a horizontally extending operating or crank shaft 54 which is arranged adjacent the bottom wall 15 of the window casement 10; this operating or crank shaft 54 carrying a manually operable handle or crank 55 which is arranged adjacent the bottom of the window and is accessible from the inner side thereof.

Mounted on the vertically extending operating rod or shaft 50 (Figs. 1 and 2), at spaced intervals thereon, are two collars 56 and 57 and each of these collars is provided with a groove 58 and 59, respectively. Working in the groove 58 of the collar 56 are two pins 60 each of which is mounted on an arm of a bell crank lever or yoke 61. Each of these bell crank levers or yokes 61 is pivotally mounted, as at 62, on a bracket 63 which is mounted on the vertically extending side wall 12 of the casement 10 and the bell crank levers 61 are pivotally connected by an angled portion 64 of a link 65. This link 65 has a second angled end portion 71 which is rockably mounted in a bracket 66 which, in turn, is mounted on the vertically extending weather-stripping member 32, on the outer side thereof (Fig. 1). Similar parts bearing the same reference numerals, followed by the letter "a," are associated with the lower collar 57 (Figs. 1 and 2).

The operation of the new window construction

which is shown in Figs. 1 to 5, inclusive, and which has been described hereinbefore is as follows:

Operation

When the window panes or sections 19, 20 and 21 are in their normal or closed position the parts are disposed in the position which the window pane or section 19 and its frame 22 and associated parts are shown in Fig. 3, with the outer portions of the vertically extending side rails 25, 26 and 27 of the window frames 22, 23 and 24, respectively, projecting into the vertically extending weather-stripping groove 31 which is formed in the side wall 13 of the window casement 10 and with the outer end portions of the vertically extending side rails or walls 34, 35 and 36 of the window frames 22, 23 and 24 projecting into the weather-stripping groove 33 which is formed in the vertically extending weather-stripping member 32.

However, when it is desired to open the window panes or sections 19, 20 and 21 this is effected as follows: The operating crank or handle 55 and its supporting shaft 54 are rotated and this movement of the shaft 54 acts, through the beveled gears 53 and 52, to rotate the vertically extending operating rod 50 and the worms 47, 48 and 49 carried thereby. When rotary motion is thus first imparted to the vertically extending operating rod 50 and its attached worms 47, 48 and 49 the worms 47, 48 and 49 (while in constant mesh with the gears 44, 45 and 46 on the shafts 38, 39 and 40) do not function at first to rotate the gears 44, 45 and 46 and their supporting shafts 38, 39 and 40, respectively, due to the fact that the outer edge portions of the rails 34, 35 and 36 of the window frames 22, 23 and 24, respectively, are seated in the vertically extending weather-stripping groove 33 which is formed in the weather-stripping member 32, thereby restraining the window frames 22, 23 and 24 and the shafts 38, 39 and 40 and the gears 44, 45 and 46, respectively, mounted thereon, from rotation. Accordingly, when rotation is first imparted to the vertically extending operating shaft or rod 50 and the worms 47, 48 and 49 mounted thereon this rotation of the worms 47, 48 and 49 which are in mesh with the gears 44, 45 and 46 but are unable at this time to rotate, causes the vertically extending operating rod or shaft 50 to be lowered somewhat, in the direction of the action of the spring 51 which normally urges the vertically extending operating rod or shaft 50 downwardly. This downward motion of the vertically extending operating rod or shaft 50 acts, through the collars 56 and 57 and the bell crank levers 61, 61a and the links 65 and 65a, and associated parts, to pull the weather-stripping member 32 away from the window panes or sections 19, 20 and 21, and their frames 22, 23 and 24, respectively, thereby moving the grooved portion 33 of the weather-stripping member out of weather-stripping engagement with the side rails 34, 35 and 36 of the window frames 22, 23 and 24, respectively.

During this movement of the weather-stripping member 32 the same engages the collars 67 on the shafts 38, 39 and 40 (which are rotatable in the openings 43 which are formed in the weather-stripping member 32) and this engagement of the weather-stripping member 32 with the collars 67 on the shafts 38, 39 and 40 moves the window panes 19, 20 and 21 and their frames 22, 23 and 24, respectively, from left to right as seen in Figs. 1 and 3, thereby sliding the side rails

25, 26 and 27 of the window frames 22, 23 and 24, respectively, out of weather-stripping engagement with the weather-stripping groove 31, which is formed in the side wall 13 of the window casement 10, much in the same manner as this result is accomplished in the above-mentioned Griffin Patent No. 2,199,562.

However, as soon as and when the grooved weather-stripping member 32 has been moved out of engagement with the side rails 34, 35 and 36 of the window frames 22, 23 and 24, respectively, and the opposite side rails 25, 26 and 27 of the window frames 22, 23 and 24, respectively, have been moved out of weather-stripping engagement with the groove 31 in the side wall 13 of the window casement 10, so that the window panes 19, 20 and 21 and the window frames 22, 23 and 24 and the weather-stripping member 32 assume the position in which the window pane 20 and its frame 23 are shown in Fig. 4, further rotary motion imparted to the vertically extending operating shaft 50 and the worms 47, 48 and 49 thereon, (by rotation of the crank 55, crank shaft 54 and gears 53 and 52, in the manner described above), causes the gears 44, 45 and 46 and their supporting shafts 38, 39 and 40, respectively, to be rotated, and this rotation of the shafts 38, 39 and 40 swings the window panes or sections 19, 20 and 21 and their supporting frames 22, 23 and 24, respectively, into open position, as indicated in dotted lines in Fig. 2.

When it is desired to close the window panes 19, 20 and 21 this may be accomplished by rotating the crank 55 and the crank shaft 54 in a direction opposite or counter to that in which the crank 55 and the crank shaft 54 are rotated to open the window panes, and this rotation of the crank shaft 54 acts, through the gears 53 and 52, to rotate the vertically extending operating rod or shaft 50 and the worms 47, 48 and 49 which are mounted thereon, thereby rotating the gears 44, 45 and 46 and their supporting shafts 38, 39 and 40, respectively, in a direction to swing the window panes 19, 20 and 21 and their supporting frames 22, 23 and 24, respectively, into closed position, whereupon further rotation of the vertical operating shaft 50 and the worm gears 47, 48 and 49 which are mounted thereon acts, through the grooved collars 56 and 57 and the yokes or bell crank levers 61 and 61a and attached links 65 and 65a, to move the weather-stripping member 32 into weather-stripping engagement with the side rails 34, 35 and 36 of the window frames 22, 23 and 24, respectively. It will be noted, in this connection, that as the weather-stripping member 32 engages the side rails 34, 35 and 36 of the window frames 22, 23 and 24, respectively, it slides these window frames and the window panes mounted thereon (from right to left, Fig. 4, into the position in which they are shown in Fig. 3) thereby moving the side rails 25, 26 and 27 of the window frames 22, 23 and 24, respectively, into weather-stripping engagement with the weather-stripping groove 31 in the side wall 13 of the window casement 10.

It will be noted, in this connection, that the spring 51 exerts a slight downward pressure upon the vertical operating rod shaft 50 and this pressure aids in effecting the immediate withdrawal of the weather-stripping member 32, when the windows are being opened, and, when the crank 55 is rotated in the reverse direction to close the windows, the downward action of the spring 51 tends to maintain the rod 50 from creeping upwardly and prematurely moving the weather-

stripping member 32 into binding engagement with the window frames 22, 23 and 24.

A slightly modified form of the new window construction is shown in Fig. 6 and all parts embodied therein which correspond to or are similar to parts embodied in the form of the invention shown in Figs. 1 to 5, inclusive, bear the same reference numerals, followed by the letter "b." This modified form of construction is substantially similar to the form of construction which is shown in Figs. 1 to 5, inclusive, except that in this modified form of construction the shaft 54b is extended horizontally in a direction parallel to the front surface of the window, instead of at right angles thereto, as is the shaft 54 in the form of the invention which is shown in Figs. 1 to 5, inclusive. Moreover, in this form of the invention the shaft 54b is extended to a point which is approximately the vertical center of the window casement, and a second or crank shaft 68, carrying a crank 55b, is extended at right-angles to the shaft 54b, these two shafts 54b and 55b being operatively interconnected by a bevel gear 69 on the crank shaft 68 which meshes with a bevel gear 70 on the shaft 54b.

While I have illustrated and described preferred forms of construction for carrying my invention into effect, these are capable of variation and modification, without departing from the spirit of the invention. I, therefore, do not wish to be limited to the precise details of construction set forth, but desire to avail myself of such variations and modifications as come within the scope of the appended claims.

I claim:

1. In a window construction of the character which includes a window casement including a vertically extending side rail member having a vertically extending opening or slot formed therein, a plurality of window frames swingingly mounted in said window casement for movement about horizontally extending axes into and out of open and closed positions and each including a vertically extending side rail, and a vertically extending weather-stripping member slidably mounted in said opening or slot for movement transversely of said window casement into and out of weather-stripping engagement with the said vertically extending side rails of the said window frames: the improvement which comprises means for operating the said window frames and the said weather-stripping member including a vertically extending vertically slidable rotatable operating member, means coacting with the said vertically extending operating member for moving the said weather-stripping member into and out of weather-stripping engagement with the said vertically extending side rails of the said window frames, the said means which coacts with the said vertically extending operating member for moving the said weather-stripping member into and out of weather-stripping engagement with the said vertically extending side rails of the said window frames, the said means which coacts with the said vertically extending operating member for moving the said weather-stripping member into and out of weather-stripping engagement with the said vertically extending side rails of the said window frames including a plurality of collars mounted on said vertically extending operating member, at spaced intervals thereon, means cooperating with said collars for moving the said weather-stripping member into and out of weather-stripping engagement with the said vertically extending side rails of the said window frames, and means, including a plurality of worms, arranged at spaced intervals upon the said vertically extending operating member, for moving the said window frames si-

multaneously into and out of open and closed positions.

2. The window construction defined in claim 1 in which each of said worms meshes with a gear mounted on the outer end portion of a horizontally extending shaft which projects through and is rotatably mounted in an opening formed in the said weather-stripping member and in which the inner end portion of each of the said horizontally extending shafts is attached to one of said window frames.

3. The window construction defined in claim 1 in which the said vertically extending operating member is normally pushed downwardly by a spring.

4. The window construction defined in claim 1 in which each of said worms meshes with a gear mounted on the outer end portion of a horizontally extending shaft which projects through and is rotatably mounted in an opening formed in the said weather-stripping member and in which the inner end portion of each of the said horizontally extending shafts is attached to one of said window frames, and which window construction embodies means for rotating the said vertically

extending operating member and in which the said means for rotating the said vertically extending operating member includes a beveled gear splined upon the said vertically extending operating member.

5. The window construction defined in claim 1 in which each of said worms meshes with a gear mounted on the outer end portion of a horizontally extending shaft which projects through and is rotatably mounted in an opening formed in the said weather-stripping member and in which the inner end portion of each of the said horizontally extending shafts is attached to one of said window frames, and which window construction embodies means for rotating the said vertically extending operating member and in which said means for rotating the said vertically extending operating member includes a beveled gear splined upon the said vertically extending operating member, and a horizontally extending and manually operable shaft which has a beveled gear thereon which meshes with the said beveled gear on the said vertically extending operating member.

LOUIS H. MORIN.
